Primary Examiner—James Gandy*Assistant Examiner*—Cathron B. Matta*Attorney, Agent, or Firm*—Harness, Dickey & Pierce, P.L.C.[57] **CLAIM**

The ornamental design for a upper portion of a bottle, as shown and described.

DESCRIPTION

FIG. 1 is a perspective view of a upper portion of a bottle embodying the principles of the present invention;

FIG. 2 is a front elevational view of the bottle seen in FIG. 1, the rear elevational view being the same; and,
FIG. 3 is a top plan view of the bottle seen in FIGS. 1 and 2.

The broken line showing of the bottom portion of a bottle is for illustrative purposes only and forms no part of the claimed design.
